Primary Examiner—Stella M Reid*Assistant Examiner*—Elizabeth J Oswecki(74) *Attorney, Agent, or Firm*—Dykema Gossett PLLC; Timothy K. Sendek(57) **CLAIM**

The ornamental design for a holiday display, as shown and described.

DESCRIPTION

FIG. 1 is a perspective view of a holiday display showing my new design;

FIG. 2 is a front elevational view thereof;

FIG. 3 is a rear elevational view thereof;

FIG. 4 is a side elevational view thereof;

FIG. 5 is an opposing side elevational view thereof; and,

FIG. 6 is a top plan view thereof.

The broken line showing of a holiday display are included for the purpose of illustrating only and forms no part of the claimed design.

The bottom view of the holiday display, which is not shown, forms no part of the claimed design.
